PILE RAISING AND LOWERING MECHANISM

Joseph Sinkovitz, Pittsburgh, Pa., assignor to
 Miller Printing Machinery Co., Pittsburgh, Pa.,
 a corporation of Pennsylvania

Application May 25, 1937, Serial No. 144,607

5 Claims. (Cl. 74—280)

This invention relates generally to a printing press and particularly to mechanism for actuating the means usually provided to receive and support a pile of sheets delivered from the press after they have been printed therein.

It is an object of my invention to provide a drive for pile-supporting means which is adapted to operate the latter under the various conditions of service usually encountered, i. e., by a rapid movement when unloading and resetting the pile-supporting means, and by a slow movement to accommodate the position of the pile support to the height of the pile as the sheets are delivered to the top thereof. In accordance with the invention, I also provide means for operating the pile support at an intermediate speed. This means cooperates with the drive last mentioned, viz., that which lowers the support gradually as the pile builds up. I also provide common means whereby the several drives may be actuated manually as desired.

A complete understanding of the invention may be gained from the following detailed description which is to be read in connection with the accompanying drawings illustrating a present preferred embodiment. In the drawings,

Fig. 1 is a side elevation, largely diagrammatic, showing the delivery end of a press having the invention incorporated therein;

Fig. 2 is a plan view; and

Fig. 3 is a sectional view along the line III—III of Fig. 1 showing parts in elevation.

The usual side frames of a printing press are indicated at 10 and 11. A pile support 12 is disposed adjacent the delivery end of the press between frames 10 and 11. The support 12 is suspended on cables 13 traversing sheaves 15, the ends of the cables being secured to winding drums 16. The drums 16 are carried on a shaft 17 journalled in the side frames 10 and 11. The sheaves 15 are journalled on shafts 18 carried on the side frames.

The end of the shaft 17 which extends through the side frame 11 traverses a sleeve 19 rotatably disposed in the frame. A ratchet wheel 20 is keyed to the sleeve. A pawl 21 mounted on the side frame cooperates with the ratchet wheel 20 to prevent counterclockwise rotation thereof.

A housing 22 is rotatable on the sleeve 19 and is disposed coaxially with the shaft 17. The housing 22 is provided with a cover 23 secured thereto by screws 24. The periphery of the cover 23 is provided with ratchet teeth 25 for a purpose which will appear shortly.

55 A gear 26 is disposed within the housing 22

and is keyed to the sleeve 19. A gear 27 is disposed beside the gear 26 but is keyed to the shaft 17. A pinion 28 is journaled on a shaft 29 carried in the housing 22 and its cover. The pinion 28 meshes with the gears 26 and 27. The latter have the same diameter, but the number of the teeth on one gear differs slightly from that on the other. Gear 26, for example, may have forty-nine teeth and the gear 27 forty-eight teeth. The teeth on one gear are slightly deformed to permit a number of teeth to be formed thereon different from the number of teeth on the other. The purpose of this arrangement will be explained presently.

A mask plate 30 overlies the ratchet teeth 25 on the cover 23, except at a portion of its periphery, for a purpose to be explained later. The plate 30 is adjustable on the cover but is normally held in fixed position by a pawl 30a carried on a bracket extending out from the frame 11. This pawl co-operates with slots 30b formed in the periphery of the plate 30 at the lower portion thereof.

A pawl disc 31 is oscillatable on the cover 23 and is secured thereon together with the mask plate 30 by a collar 32 and a holding ring 33 which may be pinned or otherwise secured to the shaft 17. The pawl disc carries a pawl 23a wide enough to overlie the mask plate and the edge of the cover 23 on which the ratchet teeth are formed. As long as the pawl rests on the mask plate, however, it is held out of engagement with the ratchet teeth. The pawl disc is oscillated by a link 23b operated by any suitable means in synchronism with the operation of the press.

The end of the shaft 17 protrudes beyond the collar 32 and ring 33, and is provided with a through-pin 34. A crank 35 has a socket with a transverse slot therein adapted to receive the pin 34, as shown in Fig. 3. A stub shaft 36 is set into the cover 23, the collar 32 being bored to receive it. The shaft 36 has its end shaped similar to that of shaft 17 so as to accommodate the crank 35 in the same manner.

A spindle 37 is journaled in the side frame 11 and a gear case 38 carried thereby. The end of the spindle 37 is so shaped as to be engageable by the crank 35 in the same manner as the shafts 17 and 36. A gear 39 keyed to the shaft 37 meshes with a pinion 40 journaled on a stub shaft 50 carried in the frame 11. A gear 42 is connected to the pinion 40 by a sleeve 43 surrounding the shaft 41. The gear 42 meshes with gear teeth 44 formed on a reduced portion of the housing 22.

The operation of the pile support by the various drives above described will now be explained.

If it is desired to raise the support 12 rapidly as, for example, after removal of a pile of sheets 5 therefrom, the crank 35 is placed on the end of the shaft 17 and turned in a clockwise direction. Such rotation of the shaft 17 is permitted by the pawl 21 and obviously is effective to wind up the cables and raise the support. As the shaft 10 17 is turned, the gear 27 turns with it. This imparts similar rotation to the gear 26 through the pinion 28. The housing 22 may rotate so that the pinion 28 moves as a planet about the gears 26 and 27. On the other hand, the friction in 15 the gears 39, 40, 42 and 44 may be such that the housing 22 remains stationary. In either event, the gear 26 is driven in the same direction as the gear 27.

When the support has been raised to the 20 proper position, the pawl 21 is effective to hold it against lowering as a result of its own weight and that of the pile thereon. The latter tends to turn the drums 16 and shaft 17 in the counterclockwise position. Any such rotation of the 25 shaft 17, of course, would turn the gear 27 with it and the gear 26 likewise, as previously explained. The gear 26, however, is keyed to the sleeve 19 to which the ratchet wheel 20 is keyed. The pawl 21 prevents counterclockwise rotation 30 of the latter, so that the support is held in raised position against the weight of the pile. This means that the shaft 17 cannot be turned counterclockwise to lower the support by applying the crank 35 directly to the shaft.

The support is lowered automatically when the 35 press is operating by the link 23b. Reciprocation of the link 23b and oscillation of the disc 31 will cause the housing 22 to be turned clockwise intermittently. The amount of angular rotation 40 imparted by the pawl 23a to the housing 22 is determined by the setting of the mask plate 30. This may be changed by pushing back the pawl 30a. Thus the support may be automatically lowered at different rates for different thicknesses of stock even though the stroke of the 45 link 23b is constant. As already stated, the gear 26 is held against counterclockwise movement because it is keyed to the sleeve 19, and the latter is prevented from counterclockwise rotation by the ratchet wheel 20 also keyed thereto and the pawl 21. The weight of the support 12 and its 50 load, however, tends at all times to turn the gear 26 counterclockwise. Clockwise rotation of the housing 22 thus causes the pinion 28 to move as a planet about the gear 26. The gear 27 is 55 driven in a counterclockwise direction by the rotation of the pinion 28 about its own axis. The gear 27, however, is also affected by the planetary movement of the pinion 28. The net result, because of the differential between the number of 60 teeth on gears 26 and 27, is that for each orbital passage of the pinion 28 about the gear 26, the gear 27 is turned one-tooth pitch in the counterclockwise direction. By this means, the support 65 12 is lowered slowly as sheets are delivered to the pile thereon.

The stub shaft 36 permits the housing 22 to be turned manually by placing the crank 35 thereon. The housing 22 may thus be turned to raise 70 or lower the support very slowly. If the support is to be raised, the pawl 23a must be thrown up.

If it is desired to operate the support either 75 up or down at a speed greater than that permitted by manual operation of the housing 22

through the stub shaft 36, the crank 35 may be disposed on the spindle 37. Manual rotation of the latter, through the multiplying gearing 39, 40, 42 and 44, drives the housing 22 at a speed several times that which is convenient by directly driving the latter through the stub shaft 36. By this means, the support may be lowered or raised at an intermediate speed less than that at which the support may be raised by applying the crank directly to the shaft 17, but considerably greater than the speeds attainable with the crank applied to the shaft 36. The pawl 21 holds the support and its load against lowering at all times, except in response to positive actuation of the housing 22 either automatically or 15 manually.

It will be apparent that the invention provides a highly flexible means for actuating the pile support at the desired speed under almost any conditions met with in normal operations. The 20 construction is relatively simple and very rugged, so that maintenance problems are reduced to a minimum.

Although I have illustrated and described herein but one preferred form of the invention, changes in the construction disclosed may be made without departing from the spirit of the invention or the scope of the appended claims.

I claim:

1. A drive for a pile support including a shaft, means for driving said shaft directly at relatively high speed, a low-speed drive for said shaft including a sun gear thereon and a planetary pinion meshing therewith, means for imparting relatively low-speed planetary motion 35 to said pinion directly, and separate means for causing such planetary motion at increased speed.

2. A drive for the pile support of a printing press comprising a shaft journalled in the side frames of the press, a sleeve on said shaft rotatable relative thereto, a housing coaxial with said sleeve and shaft and rotatable relative thereto, a pair of gears in said housing, one secured to the sleeve and the other to the shaft, a pinion journalled in the housing and meshing with both said gears, and a multiplying gear drive for said housing, said shaft, said housing and said drive each having means whereby manual operation thereof can be effected.

3. A drive for the pile support of a printing press comprising a shaft journalled in the side frames of the press, a sleeve on said shaft rotatable relative thereto, a housing coaxial with said sleeve and shaft and rotatable relative thereto, a pair of gears in said housing, one secured to the sleeve and the other to the shaft, a pinion journalled in the housing and meshing with both said gears, and a multiplying gear drive for said housing, said shaft, said housing and said drive each having means engageable by a common manual driving member adapted to be removably associated therewith.

4. A drive for a pile support comprising a shaft, means whereby said shaft may be rotated manually to effect a rapid traverse of the support, a housing rotatable about said shaft, a gear in said housing keyed to said shaft, a second gear in said housing coaxial with said first mentioned gear, a planetary pinion journalled in said housing and meshing with said gears, whereby rotation of the housing drives said shaft to effect a very slow traverse of the support, and a manually operable speed-increasing gearing for driv- 75

ing said housing to effect a traverse of said support at intermediate speed.

5. A drive for a pile support comprising a shaft, means whereby said shaft may be rotated manually to effect a rapid traverse of the support, a differential, planetary reduction gearing on said shaft including a housing rotatable there-

on, said gearing being effective on rotation of said housing to drive said shaft at slow speed, and a manually operable speed-increasing gearing for driving said housing to effect a traverse of said support at intermediate speed. 5

JOSEPH SINKOVITZ.
